UNITED STATES PATENT OFFICE.

ARTHUR H. JENKINS, OF BEVERLY, AND VINTON L. MURRAY, OF SALEM,
MASSACHUSETTS.

RACEWAY FOR LACING-HOOK-SETTING MACHINES.

1,095,576.

Specification of Letters Patent.

Patented May 5, 1914.

Application filed April 14, 1913. Serial No. 760,947.

To all whom it may concern:

Be it known that we, ARTHUR H. JENKINS and VINTON L. MURRAY, citizens of the United States, and residents, respectively, 5 of Beverly and Salem, in the county of Essex and State of Massachusetts, have invented certain new and useful Improvements in Raceways for Lacing-Hook-Setting Machines, of which the following is a specification.

This invention has for its object to enable the accumulation of lacing hooks in the raceway of a hook-setting machine to be quickly and conveniently removed from the raceway 15 preparatory to charging the same with hooks of a different color or style.

The invention consists in the improvements which we will now proceed to describe and claim.

20 Of the accompanying drawings forming a part of this specification,—Figure 1 represents a top plan view of a raceway embodying our invention and of portions of the reservoir and setting mechanism. Fig. 2 represents a front elevation of the lower end portion of the raceway and portions of the setting mechanism. Fig. 3 represents a section on the line 3—3 of Fig. 2. Fig. 4 represents a perspective view of the movable 25 portion of the raceway.

The same reference characters indicate the same parts in all the figures.

The raceway, in which our improvement hereinafter described is embodied, is of well 30 known general form and is adapted to guide a procession of lacing hooks 12 which are moved by gravity from an elevated hopper or reservoir 13 with which the upper end of the raceway communicates to suitable 35 hook-setting mechanism to which the hooks are delivered by the lower end of the raceway, a portion of the setting mechanism being shown at 14.

The reservoir and the setting mechanism 40 may be of any suitable construction, and, as our invention relates only to the lower portion of the raceway, we do not believe it is necessary to fully illustrate and describe the reservoir and the setting mechanism.

45 The raceway comprises a lower member 15, the upper edge of which is adapted to support and guide the necks of the hooks 12, and a fixed upper member 16 which is offset from the lower member 15 and has a lower 50 edge which bears upon and guides the bar-

rels or eyelet portions of the hooks, as indicated by Fig. 3. Said members are formed and relatively arranged in a well known manner to guide and control the hooks in their passage from the reservoir to the setting mechanism. 60

In carrying out our invention in the embodiment here shown, we make the lower member 15 in two parts or sections, one of which is fixed and elongated and extends 65 from the reservoir to a point near the setting mechanism, the lower end of the said fixed portion being shown at 17, Fig. 2, and forming a fixed stop or abutment for the upper end of the movable portion next described. 70

The delivering end of the member 15 is formed of a separate piece 15^a, the upper end 75 18 of which is formed to abut against the lower end 17 of the fixed portion when the movable portion is in its operative position, with its upper edge continuous with the upper edge of the fixed portion as shown by full lines in Fig. 2. The movable portion 15^a therefore constitutes a continuation of 80 the fixed portion 15, said movable portion having an upper guiding edge onto which the necks of the hooks slide from the fixed portion 15. The movable portion 15^a is adapted to swing on a fixed pivot screw or 85 stud 19 secured to a suitable fixed support 20, said pivot being so arranged that the movable portion 15^a is adapted to swing away from the lower end of the fixed portion 15, and from the fixed upper member 90 16, as indicated by dotted lines in Fig. 2. When the movable portion 15^a is thus displaced, an opening is formed between it and the lower end of the fixed portion 15 through which all the lacing hooks in the raceway 95 may escape or be quickly discharged, the hooks that were before above said opening dropping through the opening into a suitable receptacle which may be held beneath it, while the hooks that were on the movable 100 portion 15^a prior to its displacement are free to slide off from the upper edge of the displaced lower portion.

Means are provided for locking the movable portion 15^a in its operative position, the 105 said means in this embodiment of the invention comprising a U-shaped ear 22 attached at 23 to the movable portion and adapted to bestride the lower edge of the fixed portion, and a thumbscrew 24 adapted to be inserted 110

in the coinciding orifices in the ear and in the fixed portion 15. When said screw is removed, the movable portion 15^a is free to be displaced.

- 5 The novel feature of our invention is a lacing hook raceway composed of a lower neck-supporting member and an upper barrel controlling member, one of said members having a portion which is capable of
 10 quick movement to and from its operative position to permit a quick interruption of the way formed by said members, and a quick restoration of the continuity of said way. While we prefer to locate the said
 15 movable portion in the lower member of the raceway and at the extreme lower end thereof, because this location permits the removal of nearly all the hooks by gravitation, we do not limit ourselves to this particular
 20 location. The pivotal connection of the movable member to a fixed support 15^a, at one end, as shown, is preferred, because it enables the said portion to be hinged to its support by a single stud 19, and to swing
 25 edgewise thereon.

We claim:—

1. In a lacing hook setting machine, a raceway comprising a lower member, the upper edge of which forms an inclined track 30 adapted to support and guide the necks of the lacing hooks, and a fixed upper member offset from the lower member and adapted to overhang the barrels of the hooks, the lower member being composed of a fixed 35 elongated portion extending continuously from the receiving end of the raceway to a point near the delivering end, and a movable portion forming the delivering end of the lower member and movable from the fixed 40 portion and from the upper member to form an outlet for all the hooks in the raceway, including those below the fixed portion of the lower member, means being provided for locking the movable portion in its operative position.

2. In a lacing hook setting machine, a raceway comprising a lower member, the

upper edge of which forms an inclined track adapted to support and guide the necks of the lacing hooks, and a fixed upper member offset from the lower member and adapted to overhang the barrels of the hooks, the lower member being composed of a fixed 50 elongated portion extending continuously from the receiving end of the raceway to a point near the delivering end, and a movable portion forming the delivering end of the lower member, said movable portion being pivoted to a fixed support and adapted to swing away from the fixed portion and from 55 the upper member, the meeting ends of the said fixed and movable portions being provided with locking means for holding the movable portion in its operative position.

3. In a lacing hook setting machine, a 60 raceway comprising an upper guide member, and a lower guide member formed of sections, one of said sections being movable downwardly and away from the upper guide member to allow the fasteners to drop there- 65 from.

4. In a lacing hook setting machine, a raceway comprising an upper guide member, and a lower guide member formed of sections having meeting ends, one of said 70 meeting ends being movable downwardly and away from the upper guide member to allow the fasteners to drop therefrom.

5. In a lacing-hook setting machine, a raceway comprising an upper member hav- 75 ing a barrel-guiding lower edge, and a lower member having a neck-guiding upper edge, the lower member having a movable portion pivoted at one end to a fixed support, and adapted to swing edgewise away from the 80 upper member to form an outlet for the lacing-hooks in the raceway.

In testimony whereof we have affixed our signatures, in presence of two witnesses.

ARTHUR H. JENKINS.
VINTON L. MURRAY.
